UNITED STATES PATENT OFFICE.

EMILE AUGUSTIN BARRET, OF PARIS, FRANCE, ASSIGNOR TO E. BARRET ET FILS ET COMPAGNIE, OF PARIS, FRANCE, A CORPORATION OF FRANCE.

EVAPORATOR.

1,325,461.

Specification of Letters Patent. Patented Dec. 16, 1919.

Application filed June 28, 1915. Serial No. 36,396.

To all whom it may concern:

Be it known that I, EMILE AUGUSTIN BARRET, a citizen of the Republic of France, residing at Paris, in the Republic of France, have invented certain new and useful Improvements in Evaporators; and I do hereby declare the following to be a full, clear, and exact description of the invention, such as will enable others skilled in the art to 10 which it appertains to make and use the same.

My present invention relates to certain improvements in evaporators of the class in which the liquid to be evaporated is made to circulate through groups of closely assembled vertical pipes, and the principal object of the invention is the provision of means whereby the circulation may be made non-reversible and whereby the speed of circulation 20 may be so controlled at all times as to secure the most rapid transmission of heat possible. Certain features of the invention have especial reference to the regulation of the supply of the steam for heating evaporators of this type when used in a series to form a battery, as is common, for instance, in the progressive concentration of syrups in sugar manufacture.

Certain preferred forms of my improved 30 evaporator are shown in the accompanying drawings, wherein Figure 1 is a sectional view of a complete unit, some of the circulating pipes being omitted for clearness, Fig. 2 is a similar view of the upper part of a modified form, Fig. 3 is a horizontal section taken on line 3—3 in Fig. 2, Fig. 4 is a view similar to Fig. 2, but showing the mode of connection of the automatic steam regulator, Fig. 5 is a sectional view of the lower 40 part of one of my improved evaporating units, and Fig. 6 is a diagrammatic view of a battery of evaporating cells with their connections.

Where evaporators of the type here in question are used, the liquid and vapor rise together in the vertical pipes and their mode of joint progress may take either one of two forms.

In one case, where the movement in the 50 pipes of those portions of the liquid which remain unevaporated is too slow in proportion to the rate of formation of vapor in such pipes, the rising vapor masses merge as they rise to form progressively larger bubbles until finally the upper ends of the

pipes are occupied by a central current of vapor, while the interior of the walls is covered by a creeping or climbing layer of liquid. This condition is not at all favorable to rapid transmission of heat, since it 60 corresponds to a slow movement of the liquid as such.

On the other hand, when the rate of vapor formation in the tubes is properly related to the volume of liquid passing, the bubbles 65 as they merge toward the upper ends of the tubes form a series of constantly rising individual masses occupying substantially the entire cross section of each tube and divided by horizontal masses of liquid which are 70 pushed upward by the vapor like a series of pistons.

When this formation is preserved, a very rapid rate of circulation is attained with a correspondingly increased efficiency of heat 75 transmission.

The exact conditions which determine production of this latter, and more advantageous, formation cannot be predicted for all cases, since these conditions vary with 80 differences in sizes of tubes, viscosity of the liquid, boiling point, etc. It is one of the principal objects of the present invention to supply apparatus of such a nature that the operator may easily control the conditions of flow—thus putting it in his power 85 to secure the maximum of circulation and efficiency of transmission of heat.

Certain features of my apparatus are already well known, and will require only a 90 brief treatment.

In the drawings the preferably cylindrical heating drum to which the hot steam is supplied is shown at 10; the same having a top plate 11 and a bottom plate 12. Some 95 of the vertical heating tubes or pipes are shown at 13, these passing in a compact group through the heating chamber in such a manner as to lead the liquid upward from the chamber 14 to the overflow chamber 15 at the top, which last is closed by a cover 16.

As the liquid and vapor rise into the chamber 15 they pass together, through a wide lateral passage 17, into the wide return tube 18. From this the vapor rises toward the exit 19, while the liquid returns by the wide tube 20 to the chamber 14, being joined on its way by a suitable volume of new liquid supplied in a well known manner.

I have found that the proper formation of 110

vapor and liquid in the rising tubes 13 can be produced by suitably controlling the access of the liquid to the lower chamber 14, and for this purpose I cause the tube 20 to 5 terminate in a horizontal portion 21 opening downward into the chamber 14, and supply in this horizontal portion a valve controllable at will.

This valve preferably takes the form of 10 a conical plate 22 upon a stem 23, by means of which and the hand wheel 24, the opening through which the liquid may flow into the chamber 14 may be made larger or smaller at will. By this means the pressure 15 at the base of the tubes 13 may be regulated, and the desired speed of ascent of liquid in these tubes may be secured.

I am aware that it has been proposed to 20 employ an apparatus of the general type above described in combination with a horizontal primary generator below it connected with the lower chamber, and to supply a pipe connecting the upper chamber with one 25 end of the primary generator. This arrangement does not permit ready and accurate control of the rate of circulation and is not intended for this purpose. This is principally because the return pipe does not furnish a direct return from the upper to 30 the lower chamber, and the return flow is complicated in its behavior by the varying and non-ascertainable conditions of pressure within the horizontal primary generator. For this reason I have distinguished 35 certain of my claims from the earlier construction above mentioned by mentioning that the return pipe is open and direct-connected to the lower chamber.

To insure non-reversibility of circulation, 40 I prefer to carry the top of the heating drum 10 above the bottom of the upper chamber 15, thus forming a circular channel around the drum 10 as shown in Fig. 3. I also prefer to slope the top of the drum 10 either 45 in a plane inclined toward the passage 17 as in Figs. 2 and 4, or in a dome shape, as in Fig. 1. I also find it best to extend the ends of the pipes 13 above the top of the drum 10, so that there may be no superin- 50 cumbent mass of liquid tending to produce a reverse circulation. Where the dome shape is used at the top of the drum 10, it is best to give the same shape to the bottom there- 55 of, as shown in Fig. 1. This makes it possible to make all the tubes 13 of the same length.

It will be seen that this structure causes 60 a quick delivery of the liquid to the return pipe, without possible back pressure. The same result would follow from making the top of the drum 10 concave with a wide return pipe leading back to 14 from the lowest point of the concave. This quick return of the liquid is further facilitated by the form 65 of the channel surrounding the top of the

drum 10. As shown in Fig. 3, this gutter is narrowest on the side opposite the return tube 18, and widens toward that tube on both sides of the drum 10.

I prefer to provide means for automatic 70 regulation of the pressure of live steam supplied to the drum 10. This is particularly desirable where my evaporators are used in batteries. In Figs. 1 and 4 of the accompanying drawings I have shown a 75 form of apparatus, already familiar in other connections, which is claimed herein only in combination with a battery of evaporators fed with live steam for heating purposes. The admission valve for the live 80 steam is shown at 28, the same being controlled by the float shown in dotted lines within the closed chamber 27. This chamber is placed over another closed chamber 26, with which it communicates by a vertical tube, as shown, which reaches nearly to the bottom of the lower chamber 26.

There is a body of water within the lower chamber more or less of which is forced up 90 into the chamber 27 by the pressure of the live steam in the drum 10, exerted through the tube 25, upon the top of the body of water. When the pressure drops in the drum 10, the water rises in the lower chamber, the float moves downward in the upper 95 chamber, and the valve 28 is operated to increase the supply of live steam. When, on the contrary, the pressure rises in the drum 10, the water rising under the float in the chamber 27 causes it to partly close 100 the valve 28 to diminish the steam pressure. The three valves 29, 30 and 31, communicating with the overflow 32 provide means for varying the effective level of the water in vessels 26 and 27, so as to regulate the apparatus. 105

In regulating a battery it will be sufficient to connect a single regulator with one member of the series (preferably the second or third) and to select, by preference a unit 110 in which the boiling point is from 102 to 104 degrees C. This margin is generally sufficient for the variable speeds to be produced in this apparatus.

The mode of connecting up a number of 115 evaporators in a battery for the purposes of this invention is shown in Fig. 6 in a battery of three evaporators. The liquid to be evaporated enters the first cell through the pipe 33, and, after passing through the circulation system of that cell, passes to the second by the pipe 34. From this cell it passes to the third cell by the pipe 35, and is finally discharged through the valve 36 in the pipe 37. In this arrangement the regulator 26, 27, receives the pressure from the second cell of the series through the pipe 25. By the employment of my improved evaporators connected in a battery in this manner it is possible to regulate the amount of liquid 120 125 130

delivered to the first cell automatically by simply regulating the flow at the exit pipe by means of the valve 36.

It is obvious that the proportions of the 5 regulator must be suited to the actual pressure existing in that unit of the series chosen as a basis of regulation. If, for instance, this pressure is to be a half kilogram, the two chambers of the regulator must be separated correspondingly. If higher pressures are required a mercury regulator may be used; but this is unnecessary where the regulator for a battery is applied to the second or third unit in the series wherein lower 10 pressures exist than are found in the first. The entire battery is thus regulatable by reactions among the successive units.

The principal advantages of the arrangements above described are as follows:

20 To control the returning downward flow so as to give strictly the appropriate rate of circulation for a maximum evaporation; and to make it possible to regulate the flow with these ends in view so that it shall be slow, 25 medium or swift according to the given conditions to be met.

To assure free flow of liquid from the upper ends of the vertical heating tubes and to make the system strictly non-reversible.

30 To regulate automatically the quantity of steam sufficient for the different speeds of circulation and to accomplish this by application to the second or third unit in a series.

What I claim is—

35 1. In an evaporating unit of the class described, a heating drum, a lower chamber, an upper chamber, wider than said drum and including a channel around the top of the drum and below the level of the top 40 thereof, said channel widening gradually from one side of said chamber to the other, a group of tubes leading through said drum from one chamber to the other and having their upper ends projecting above the top

of the drum and above the normal level of 45 the liquid contents, and a wide return tube placed outside of the heating influence of the drum and connecting said lower chamber with that side of the upper chamber where said channel is widest.

50 2. In an evaporating unit of the class described, a heating drum, an upper chamber, a lower chamber, a group of substantially vertical tubes leading through said drum from one of said chambers to the other, a 55 wide return pipe leading from the top to the bottom chamber and having a substantially horizontal end projecting into said lower chamber, and a valve adapted to be moved from outside, to regulate the flow from said 60 return pipe into said lower chamber.

3. In an evaporating unit of the class described, a substantially vertical heating drum, a lower chamber and an upper chamber, a wide return tube leading back from 65 the bottom of the upper chamber to the lower chamber and having a dome at its top above said upper chamber, and a valve in said return tube.

4. In a battery of evaporator units of the 70 class described each having a heating drum adapted to receive steam for heating purposes, an automatic and adjustable pressure regulator for said steam applied to one of the units after the first, substantially as described, so as to regulate the entire battery by the reactions between the successive units, 75 said regulator comprising a valve, a float, a pressure-column of water and means for subjecting said pressure-column to the pressure of steam existing in the heating drum of the unit to which the regulator is applied.

80 In testimony whereof, I affix my signature, in presence of two witnesses.

EMILE AUGUSTIN BARRET.
